REFRIGERATING APPARATUS

Andrew A. Kucher, Oakwood, and Alex A. McCormack and Glenn W. Wolcott, Dayton, Ohio, assignors to General Motors Corporation, Dayton, Ohio, a corporation of Delaware

Application January 17, 1941, Serial No. 374,908

2 Claims. (Cl. 257—140)

This invention relates to heat exchangers and particularly heat exchangers formed of sheet metal plates.

An object of our invention is to provide an improved heat exchanger constructed substantially in its entirety of thin gauge sheet metal plates arranged in secured together pairs to form a compact structure having a maximum of heat transfer surfaces by rendering all portions of the plates except small abutting portions thereof direct heat flow paths between a fluid within the structure and a medium exteriorly thereof.

Another object of our invention is to provide a heat exchanger of the type wherein a plurality of thin metal plates are fabricated in such a manner that when secured together in pairs to provide a closed fluid passageway between the groups of plates the walls of the passageways are of an improved form or contour which will withstand high pressure.

Another object of our invention is to form a heat exchanger from a plurality of thin metal plates secured together in pairs which plates are prefabricated with dimple-like depressions including flat portions and intermediate connecting portions and wherein all the flat portions of the plates are in abutting relation and the spaced apart intermediate portions of the plates provide continuously curved or arcuate wall surfaces of fluid passageways between the plates of the pairs thereof for increasing the strength of the walls of the passageways.

A further object of our invention is to provide a condenser for a refrigerating system by abutting portions of thin metal plates of pairs thereof having refrigerant passageways therebetween and securing wall parts of apertures in one plate of one pair thereof to wall parts of apertures in a plate of another pair to form spaced headers extending along the length of the condenser, and wherein the secured together walls of the apertures may form the sole means for locking the pairs of plates together and for holding the abutting portions of the plates of the various pairs against one another.

A still further object of our invention is to provide a heat exchanger or condenser of the type set forth in the preceding objects wherein the sheet metal plates of each pair thereof are provided with dimple-like depressions over substantially their entire area and wherein the depressions include spaced apart flat portions and curved or arcuate portions intermediate the flat portions which are arranged to provide the passageway between the plates of each pair of plates

with opposed convex wall surfaces for increasing the strength thereof to withstand high internal pressure.

Further objects and advantages reside in the cooperation of parts of the structure which facilitate the manufacture and assembly of our improved exchanger and in the novel combination and arrangement to provide a strong efficient unit of low manufacturing costs as will more fully appear in the course of the following description.

In the drawings:

Fig. 1 is a diagrammatic showing of a refrigerating system having a condenser constructed in accordance with the present invention therein;

Fig. 2 is an enlarged fragmentary front view partly in section and partly in elevation of the pairs of plates forming the condenser shown in Fig. 1;

Fig. 3 is an end view of the condenser shown in Fig. 2;

Fig. 4 is an enlarged fragmentary view taken on the line 4—4 of Fig. 2 showing a portion of the face of a plate of one of the pairs thereof in the condenser;

Fig. 5 is a sectional view taken on the line 5—5 of Fig. 4 showing the contour of walls of a passageway formed between the plates of a pair of plates of the condenser and showing the locking of the pairs of plates to one another;

Fig. 6 is a sectional view taken on the line 6—6 of Fig. 4 showing button-like depressions in the plates and passages which connect portions of the passageway between the plates together; and

Fig. 7 is a fragmentary sectional view taken on the line 7—7 of Fig. 4 showing the button-like depressions and other contacting portions of the plates of the condenser.

There is shown in Fig. 1 of the drawings, a diagrammatic illustration of a closed refrigerating system wherein a sealed motor-compressor unit 10 withdraws evaporated refrigerant from an evaporator 11 through a conduit 12, compresses the evaporated refrigerant and forwards the compressed fluid to a heat exchanger or condenser, constructed in accordance with our invention and generally represented by the reference character 14, by way of a conduit 15. Air flowing over or caused to be circulated through condenser 14 cools the compressed refrigerating fluid and liquefies the same. The condensed liquefied refrigerant collects in the lower portion of condenser 14 and is directed by a pipe 16, to

the evaporator 11. A suitable restrictor or restricting device 17 may be employed for controlling the amount of liquid refrigerant entering the evaporator. Starting and stopping of the motor and consequently the compressor of the motor-compressor unit 10, is controlled in response to the refrigerating effect produced by the evaporator. Thus, a thermostat bulb 19 is provided in heat exchange relationship with the evaporator and this bulb is connected with an expandible and contractible bellows 21 of a snap-acting switch 22, by a pipe 23. Switch 22 controls the opening and closing of contacts interposed in an electric circuit leading to the unit 10. Operation of the motor-compressor unit 10 under ordinary demands of refrigeration of the refrigerating system subjects the condenser to normal internal pressures and abnormal demands of refrigeration by the refrigerating system or operation of the system during abnormally high temperatures causes the interior of the condenser to be subjected to relatively high pressures. The condenser 14 is constructed substantially in its entirety of sheet metal plates to obtain relatively flat wide refrigerant condensing passageways and these plates are as thin as possible to reduce manufacturing costs of the condenser. Thus, the plates must be fabricated to provide strong walls for the refrigerant passageways in order to withstand high internal pressures which frequently occur in a closed refrigerating system.

The condenser 14 is of a box-like form and is composed of a plurality of long relatively narrow pairs of secured together thin metal members or plates. The plates of each of the plurality of pairs thereof are fabricated or recessed to provide dimples 27 (see Figs. 2 and 4) over substantially their entire surface area. The plates are all recessed in the same direction and one plate 28 is reversely placed against another plate 29 to form two-plate pairs and these pairs of plates are disposed one against another to provide a condenser structure or heat exchanger of the desired length. One plate 28 of each pair thereof is slightly larger than the other plate 29 of the pair and has its peripheral edge portions 31 bent over the peripheral edges 32 of plate 29. Each plate 28 and 29, of the pairs of plates, is provided with an aperture therein adjacent each end thereof. The walls 33 of the apertures in plates 28 are flanged inwardly of the pairs and the walls 34 of the apertures in plates 29 are flanged outwardly. The walls 34 of the apertures in plates 29 telescope or fit into the walls 33 of the apertures in plates 28 (see Fig. 5) and have their edge portions bent or spun over and secured to the edge portion of the walls 33 to lock the pairs of plates together. The depressions or dimples 27 in plates 28 and 29 include spaced apart flat portions 36 and intermediate continuously curved or arcuate portions 41. The depressions or dimples 27 are oppositely disposed when the plates 28 and 29 are secured together to provide the pairs of plates. Plates 28 and 29 have contacting wall portions 37 (see Figs. 5 and 6). Spaced apart portions of plates 28 and 29 form a relatively flat wide fluid passageway between the plates of each pair thereof and the curved or arcuate portions 41 provide spaced apart opposed convex wall surfaces for the passageway. The contacting portions 37 of each pair of the plates 28 and 29 are deformed one into the other to provide a plurality of small round interfitting button-like depressions 38 (see Figs. 6 and 7) which provide a mechanical connection 75

between the plates of each pair thereof intermediate their edges for a purpose to be hereinafter described. It will be noted that the dimples 27 and the button-like depressions 38 are arranged in vertical and horizontal rows over substantially the entire surface area of the pairs of plates. The contacting portions 37 or button-like depressions 38 are located at the center of four of the dimples 27 to thus provide the narrow communicative passages 39 between the wider portions of the closed passageway formed by spaced apart flat portions 36 of the dimples. The spaced apart flat portions 36 of one plate 28 of a pair of plates 28 and 29 engages or abuts the corresponding spaced apart flat portions 36 of the adjacent plate 29 of another pair of plates. The portions 41 of the dimples 27 provide continuously curved or arcuate wall surfaces for the passageway between the plates 28 and 29 and, between the secured together points 37 and 38 of the plates and the space between the dimpled depressions 27 of the pairs of plates, form a plurality of air passages 40 extending transversely through the heat exchanger. It will be noted that a relatively flat wide confined fluid passageway is provided between the plates 28 and 29 of each pair thereof and that the securing of walls 33 and 34 of the apertures in the plates provide spaced apart headers extending along the length of the exchanger and communicating with each of the closed fluid passageways. The continuously curved or opposed convex wall surfaces 41 for the fluid passageway between the plates of each pair of plates affords a wall structure for the passageway which is of increased strength and capable of withstanding high pressures. This increased strength is obtained by forming all portions of the walls of the passageways, except the abutting or secured together portions thereof, with a continuously curved surface or a surface that is curved in a direction opposite the direction of application of internal pressure thereto. The abutting flat points or portions 36 of the pairs of plates distribute pressure within any one passageway to other pairs of plates. Thus, the wall surfaces 41 and contacting flat points 36 cooperate with one another to provide increased structural strength of the thin plates of the condenser. A relatively heavy plate 42 having a mounting bracket 43 thereon is secured to each end plate of the heat exchanger or condenser 14. One end of each of the headers within the condenser structure 14 is closed by a plug 44 (see Fig. 2) and the other end of each header is provided with a suitable elbow pipe 46 to form a fluid inlet and a fluid outlet for the condenser 14. The plates 28 and 29 of condenser 14 may be individually assembled together with the proper bending of their edges and spinning of walls of the apertures therein and thereafter the structure may be placed in a brazing furnace with a suitable spelter and bonding material located within the passageways and headers of the assembled condenser. The structure will, upon being heated in the furnace, cause bonding together of contiguous portions of the metal plates 28 and 29. Such assembling and brazing of the plates together is conventional and well known to those skilled in the art and it is to be understood that the end plates 42, plugs 44 and elbow pipe connecting means 46 may be brazed to the plates at the same time the plates are brazed to one another.

Metal members or plates 28 and 29 are approximately .012 inch in thickness and the prefabrication thereof with the plurality of dimple-

like depressions 27 greatly increases the structural strength of walls of passageways between the plates over that ordinarily obtainable from metal walls of such thickness. The fabrication of the thin metal as described and their being secured together at their edges and at a plurality of points intermediate their edges and adjacent the dimples 27 prevent the plates from buckling or bulging upon the occurrence of high pressure within the structure. Abutment of the flat portions 36, of dimples 27 of the plates of one pair of plates, with the corresponding flat portions 36 of dimples 27 of the plates of other pairs of plates, increases the structural strength of the structure in that internal pressure is distributed at a plurality of points and over a wide area to prevent spreading apart of the pairs of plates. By this construction and arrangement the secured together wall portions 33 and 34 of the apertures in the plates function or serve to form the sole means of locking the pairs of plates of the structure together. The necessity of providing additional tying means across the length of the structure either internally or exteriorly thereof is eliminated.

By fabricating the metal at the contacting points 37 of plates 28 and 29 to form the button-like depressions 38, we provide a small irregular contiguous surface at the abutting points between the plates of each pair thereof and these surfaces, when bonded together, are strong and not likely to be separated by pressure within the closed fluid passageway between the plates.

From the foregoing, it will be seen that we have provided an improved heat exchanger and particularly a condenser for a refrigerating system which is made substantially in its entirety of thin sheet metal plates. The condenser is of low manufacturing costs and highly efficient since the refrigerant cooling and condensing passageways are flat and wide to spread the refrigerating fluid over a large area and to expose both sides of the spread-out refrigerant fluid to air flowing through or circulated over the condenser. The thin metal sheets with which the condenser is constructed can be readily punched and fabricated and thereafter brazed together in a bank comprising pairs of the sheets to form the plurality of interconnected closed fluid passageways. Our improved condenser is compact and efficient in that it affords the maximum of heat transfer surface within a given area and provides for an effective flow of air over the fluid passageways thereof. Contacting portions of the plates of the condenser rapidly transfer heat from one portion to another portion thereof to dissipate the heat to the atmosphere and thereby reduce the temperature gradient between portions of the condenser. The contacting portions of the plates together with the continuously curved wall portions of the dimples adjacent the contacting portions thereof divide internal pressures

over large areas and prevent buckling and bulging of the walls of the fluid passageways to thereby afford a structure of increased or improved structural strength.

5 While the form of embodiment of the invention as herein disclosed, constitutes a preferred form, it is to be understood that other forms might be adopted, all coming within the scope of the claims which follow.

10 What is claimed is as follows:

1. A heat exchanger comprising a bank of pairs of plates, each plate being formed with dimple-like depressions arranged in mutually substantially perpendicular series of rows, the two plates of each pair having their dimple-like depressions in opposed relationship and being spaced apart throughout said rows to provide a fluid passageway between the two plates, the plates of each pair being secured together at their edges and at 15 points forming rows alternating with the first mentioned rows, said depressions having flat base portions and interiorly convexly curved side portions, the flat base portions of the depressions of one pair of plates abutting corresponding flat base portions of the depressions of adjacent pairs of plates, the dimple-like depressions in said rows in each plate being contiguous to one another and the curved side portions of the depressions in each pair of plates providing opposed 20 interiorly continuously convex wall surfaces for said fluid passageway between said flat base portions wherever it may be subjected to internal fluid pressure.

2. A heat exchanger comprising a bank of pairs of plates, each plate being formed with dimple-like depressions arranged in mutually substantially perpendicular series of rows, the two plates of each pair having their dimple-like depressions in opposed relationship and being spaced apart 25 throughout said rows to provide a fluid passageway between the two plates, the plates of each pair being secured together at their edges and having nested portions diagonally between the dimples of adjacent rows, each of said depressions having a flat base portion and an interiorly continuously convexly curved side portion, the flat base portions of the depressions of one pair of plates abutting corresponding flat base portions of the depressions of adjacent pairs of 30 plates, the dimple-like depressions in said rows in each plate being contiguous to one another and the curved side portions of the depressions in each pair of plates thereby providing opposed 35 interiorly convex wall surfaces for said fluid passageway continuously along said rows between the wall surfaces thereof provided by the flat base portions of the opposed spaced apart dimple-like depressions in each pair of plates.
